(57) **CLAIM**

The ornamental design for a cup, as shown and described.

DESCRIPTION

FIG. 1 is a perspective view of a cup, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view of the cup, shown attached to a lid;

FIG. 9 is a front elevation view thereof, shown attached to a lid;

FIG. 10 is a rear elevation view thereof, shown attached to a lid;

FIG. 11 is a left side elevation view thereof, shown attached to a lid;

FIG. 12 is a right side elevation view thereof, shown attached to a lid;

FIG. 13 is a top plan view thereof, shown attached to a lid; and,

FIG. 14 is a bottom plan view thereof, shown attached to a lid.

The broken lines in the drawings illustrate environmental structure, specifically the lid in FIGS. 8-13, that form no part of the claimed design.

1 Claim, 12 Drawing Sheets
